(57) **CLAIM**

We claim the ornamental design for a baby sling, as shown.

DESCRIPTION

FIG. 1 is an isometric view of a baby sling showing our new design;

FIG. 2 is a top plan view thereof;

FIG. 3 is front view thereof;

FIG. 4 is a side elevation view thereof; and,

FIG. 5 is a bottom plan view thereof.

The broken lines shown on the surface of the article throughout the views are understood to represent stitching.
